UNITED STATES PATENT OFFICE.

CHARLES F. HALDEMAN, OF SALEM, OHIO, ASSIGNOR TO THE SILVER MANUFACTURING COMPANY, OF SALEM, OHIO, A CORPORATION OF OHIO.

FEED-CUTTER.

1,027,537.

Specification of Letters Patent.

Patented May 28, 1912.

Application filed January 7, 1910. Serial No. 536,831.

To all whom it may concern:

Be it known that I, CHARLES F. HALDEMAN, a citizen of the United States, residing at Salem, in the county of Columbiana and 5 State of Ohio, have invented a new and useful Improvement in Feed-Cutters, of which the following is a specification.

My present invention relates more specifically to the cutter heads in feed cutters; and 10 the objects of my invention are to generally improve such parts as my invention pertain to in feed cutters and to provide a simple and easily constructed device whereby the knives of the cutter head can be more readily 15 adjusted upon the cutter head proper to and from the shear plate. I attain these objects by the construction illustrated in the accompanying drawings, in which—

Figure 1 is a top plan view of the cutter 20 head and shear plate. Fig. 2 is an end view of the cutter head showing parts in section. Fig. 3 is a detached view of the knife holding adjustable block. Fig. 4 is a perspective view of a portion of one of the knife carrying spiders.

Similar numerals of reference indicate corresponding parts in all the figures of the drawings.

In the accompanying drawing, 1 represents the shaft, which shaft is journaled in 30 bearings common to feed cutters and to which shaft power is applied to rotate the shaft together with the different parts attached thereto. Upon the shaft 1 are securely mounted the spiders or end heads, 35 which end heads are made up of the hubs 3 and the arms or spokes 4, said arms or spokes being provided with the radial extensions or continuations 5 and the forward 40 extending flanges 6. The outer surfaces of which are concaved as illustrated in the drawings. Upon the flanges 6 are located the knife holding blocks 7, the inner surfaces of which are convexed, the convexity 45 corresponding with the curvature of the outer faces of the arms 6. The arms 6 are each provided with the elongated slots 8, through which elongated slots are located the knife clamping bolts 9, said knife clamp- 50 ing bolts also extend through the blocks 7 and the knives 10, the clamping bolts 9 being so attached to the knives 10 that there can be no relative movement as between said knives and the clamping bolt. The radial exten- 55 sions 5 are provided with screw threaded

apertures 11, through which screw threaded apertures the bolts 12 pass. The screw threaded bolts 12 are for the purpose of preventing any backward movement of the knives 10, together with the blocks 7. 60

It will be understood that in feed cutters it requires considerable force to thrust the knives through the material designed to be cut and hence it is of importance to prevent any backward or sliding movement of the 65 knives 10 and the heads 7, which backward movement is largely prevented by means of the bolts 12. For the purpose of holding the knives 10 in proper relationship with reference to the heads 7, said heads are provided with the flanges 13 against which flanges the knives 10 abut at or near the ends. When it is desired to adjust the cutting edges of the knives 10 to or from the shear 70 plate 14, the nuts 15 are rotated in the direction to loosen the clamped parts so that the bolts 12 are free to move in the elongated slots 8, at which time the knives 10 and their holding blocks 7 can be moved in either direction upon the flanges 6, which adjustment is made by rotating the bolts 12 and crowding the blocks 7 forward or by moving the bolts 12 backward and setting the backs of the blocks 7 against the ends of the bolts. After the proper adjustment has 75 been made with reference to the knives 10 and shear plate 14 the bolts 12 are locked against accidental rotation by means of the jam-nuts 16. 80

The object and purpose of concaving the 85 outer faces of the arms 6 and curving the adjacent faces of the blocks 7 is to provide means for moving the blocks 7 in such a manner that said blocks move when adjusted in a tangential curve, thereby, moving 90 the cutting edges of the knives forward in the arc of a circle and at the same time bring the edges of the knives to or from the shear plate 14 and to or from the axis of the cutter head proper. It will be understood that by 95 providing this compound movement of the knives 10 during the time they are being adjusted or moved they can be set at the desired angle with reference to the diameter of the cutter head proper and at the same 100 time providing a greater range of adjustment within a given space. 105

As shown in Fig. 1, the knives 10 are so located upon the head proper that as the cutter head is rotated in the usual manner a 110

shear cut will be made by the knives. It will also be understood that the knives should be curved in such a manner that a continuous shear is maintained from end to end of the knives. This feature as to the curvature of the knives and the longitudinal adjustment of the knives is common and well known. For the purpose of permitting the curved tangential movement of the knife holding block 7 through which the bolts 12 pass, the bolt apertures 17 should be tapered as illustrated in Fig. 2.

Having fully described my invention what I claim as new and desire to secure by Letters Patent, is—

In a feed cutter a shaft, knife-carrying heads spaced from each other and secured to said shaft and rotated therewith, said heads consisting of hubs, spokes, said spokes provided with forward extended flanges, radial extensions located at the rear of the forward extending flanges and provided with screw threaded bolts, means for locking the screw threaded bolts against accidental rotation, 25 knife holding heads provided with flanges

and tapered apertures, knives secured to said knife holding heads and the flanges upon the heads adapted to abut against the backs of the knives and the screw threaded bolts adapted to abut against the backs of 30 the knife - holding heads, screw threaded bolts carried by the extensions, said extensions provided with outer concaved faces and the knife holding block provided with convexed faces adapted to fit the concaved faces 35 of the extensions, clamping bolts located through the knives and forward extending flanges and through the tapered apertures in the knife holding heads thereby providing means for a rocking movement of the 40 knife holding heads, substantially as and for the purpose specified.

In testimony that I claim the above, I have hereunto subscribed my name in the presence of two witnesses.

CHARLES F. HALDEMAN.
